UNITED STATES PATENT OFFICE

2,398,786

CHAIN DREDGE BUCKET AND METHOD OF FORMING

George R. Hanks, Clinton, N. J., assignor to Taylor-Wharton Iron and Steel Company, High Bridge, N. J., a corporation of New Jersey

Continuation of application Serial No. 427,651, January 21, 1942. This application January 25, 1944, Serial No. 519,669

5 Claims. (Cl. 29—148)

This invention relates to a method of forming the rear eye of chain dredge buckets and providing the same with lining metal and to a chain dredge bucket provided with a novel rear eye, this application being a continuation of my application Serial No. 427,651, filed January 21, 1942, for Chain dredge buckets.

My invention was devised to correct certain defects and disadvantages inherent in the construction and operation of chain dredge buckets of the conventional type in respect more particularly to the rear eye provisions for establishing, in conjunction with the front eyes, articulation or pintling action of two or more buckets.

It has been the practice for many years, as is well known to those skilled in the art, to make these buckets in the form of solid or integral castings of manganese steel. The buckets are cast with a single relatively wide rear eye and with a pair of front eyes adequately spaced apart so as to receive between them the rear eye of the next adjacent bucket, the two sets of eyes providing for articulation of the buckets by appropriate pintle connection.

Manganese steel is employed because that metal, when properly heat-treated, has a characteristic paradoxical tough hardness which makes for long life. However, the casting and heat-treatment of steel alloys of this type is a serious problem especially when there is a marked inequality of metal section. Nor is the problem solved simply by overcoming casting difficulties. It is solved only by proper heat-treatment of a good casting because it is the heat-treatment that accounts for the tough hardness peculiar to manganese steel. And, although the casting and heat-treatment of manganese steel buckets makes their initial cost relatively high, their long life and general all-around ability to cope with the rigors of dredging makes it an economy to use them.

The rear eye of the conventional chain dredge bucket is cast with concentric arcuate walls. The larger arc serves to accommodate an insertible and replaceable manganese steel bushing of substantially semicircular section. The purpose of the smaller arc is to prevent rotary shifting of the bushing and, to that end, has anvil surfaces or shoulders in abutting relation with the arms of the bushing. Such differential arc construction makes for inequality of metal section and, hence, gives rise to foundry difficulties in casting and heat-treatment so that an apparently sound casting may have inherent or potential zones of weakness located radially near the corners of the shoulders. To minimize the

danger from cracks which are invited by sharp corners, these shoulders are made with considerable radii in the corners, and the bushing edges are similarly rounded. This necessarily reduces the bearing area between the abutting parts.

5 The severe battering of the bushing edges against the shoulders impairs them to a degree such that they are not long effective to hold the bushing rigidly stationary, with the result that 10 the pintling is off center and this condition is reflected in the pitch of the whole chain of buckets.

According to my invention, chain dredge buckets are cast with a rear eye free of bushing stops 15 or the like offset provisions tending to create inequality of metal section. Dredge buckets so characterized are described and claimed in Patent No. 2,280,141, granted April 21, 1942. The rear eye so formed is ground or machined so that it presents 20 a symmetrically full round or cylindrical bore for the reception of lining metal to receive the barrel of the linkage pin in coaxial relation with the front eyes. The lining comprises facing arcuate members whereof one is a wear-compensating 25 bushing, and whereof the other is a filler, or bushing stop.

25 The bushing stop is adapted and arranged for positive interlocking connection with the rear eye in order adequately to function to prevent 30 rotary shift of the bushing. The bushing stop may preferably be a unitary structure insertible from either end of the rear eye or it may be in sectional lengths. In either case the outer ends 35 of the bushing stop are welded to the bucket by the electric arc process.

35 The bushing and bushing stop may be pre-conditioned in order to minimize peening or cold flow after the manner set forth in my U. S. Patent No. 1,701,976, granted Feb. 12, 1929.

40 My improvements and the manner in which the benefits flowing therefrom may be realized in practice, will be readily apparent to those skilled in the art by reference to the accompanying drawings, wherein:

45 Figure 1 is a plan view showing my improvements.

Fig. 2 is a longitudinally sectional view of a rear eye showing my improved assembly in which a one piece filler or bushing stop is positively anchored with relation to the rear eye stock.

50 Fig. 3 is a cross section of the bucket eye showing full bearing contact of the abutting surfaces of the bushing and bushing stop, and welds at ends of bushing stop.

55 Fig. 4 is a longitudinally sectional view of the

preferred assembly including a filler or bushing stop.

Fig. 5 is a detail in cross section of one of the abutting contacts of bushing and filler stop, showing entire absence of radii on the corners and therefore full width bearing for insuring long life.

In the more or less schematic showing, Figure 1, a chain dredge bucket is indicated at 5, its rear eye at 6, and its front eyes at 7. The rear eye of one bucket coordinates with the front eyes of the immediately adjacent bucket by means of a linkage pin.

In a simple embodiment of the invention, the bushing 8, Fig. 2, which may be the conventional bushing, is retained in proper functioning position by a filler or lining member 9. The latter is formed in substantial coincidence with the bushing, that is to say, it is a unitary arcuate shaped member substantially the major dimension of the rear eye, the main difference between the two lining members being that the stop or filler is secured in positive fashion against angular or rotary movement in order that it, in turn, will be capable of successfully resisting rotary shift of 25 the bushing. One way of accomplishing this is to provide the rear eye with a through slot 10 to receive a corresponding offset or key 11 ranging medially and longitudinally of the bushing stop. The assembly bushing complement 9 is applied from either end of the rear eye and is secured against longitudinal movement in any appropriate way, preferably the outer ends of the key 11 and filler 9 are beveled as at 12 whereby, in conjunction with adjacent portions of the rear eye, a substantially V-shaped pocket is formed for the reception of weld deposit metal 13.

Under preferred practice the filler or bushing stop 9 is in one length as in Fig. 3, and is provided with a dovetail key 11. The rear eye has a complementary slot 10 shaped to fit the key, and provides a tongue and groove interlock. Likewise in this embodiment, or in any other embodiment within the scope of my invention, provision is or may be made for differential hardness of the bushing and bushing stop members, particularly at the impact areas thereof.

Having described my invention, I claim:

1. The method of forming a lined rear eye of a chain dredge bucket which includes the steps of casting the bucket with a rear eye which is substantially circular in cross section, machine grinding the interior cylindrical wall of said eye, separately providing an approximately semicircular stop member having abutment end surfaces of the full thickness of said member, dovetailing said stop member with the forward segment of said eye, and thereafter inserting in the rear segment of said eye an approximately semicircular renewable bearing bushing with its end surfaces

in abutting relation to the end surfaces of said stop member.

2. The method of forming a lined rear eye of a chain dredge bucket which includes the steps of casting the bucket with a rear eye which is substantially circular in cross section, machine grinding the interior cylindrical wall of said eye, separately providing an approximately semicircular stop member having abutment end surfaces of the full thickness of said member, dovetailing and welding said stop member to the forward segment of said eye, and thereafter inserting in the rear segment of said eye an approximately semicircular renewable bearing bushing with its end surfaces in abutting relation to the end surfaces of said stop member.

3. The method of forming a lined rear eye of a chain dredge bucket which includes the steps of casting the bucket with a rear eye which is substantially circular in cross section, machine grinding the interior cylindrical wall of said eye, separately providing an approximately semicircular stop member having abutment end surfaces of the full thickness of said member, forming a dovetail interlock between said member and the forward segment of said eye throughout the axial width of said member, welding said member to the wall of said eye, and thereafter inserting in the rear segment of said eye an approximately semicircular renewable bearing bushing with its end surfaces in abutting relation to the end surfaces of said stop member.

4. The method of forming a lined rear eye of a chain dredge bucket which includes the steps of casting the bucket with a rear eye which is substantially circular in cross section, machine grinding the interior cylindrical wall of said eye, separately providing an approximately semicircular stop member having abutment end surfaces of the full thickness of said member, hardening the abutment end surfaces of said member, dovetailing and welding said member to the forward segment of said eye, and thereafter inserting in the rear segment of said eye an approximately semicircular renewable bearing bushing with its end surfaces in abutting relation to the end surfaces of said stop member.

5. A chain dredge bucket cast with a rear eye which is substantially circular and machine ground, an approximately semi-circular stop member dovetailed into and welded to the forward segment of the eye and providing abutment end surfaces of the full thickness of said stop member, said end surfaces being hardened, and an approximately semi-circular renewable bearing bushing in the rear segment of the eye and contacting with the hardened end surfaces thereof to prevent circumferential movement of said bushing.

GEORGE R. HANKS.
